M. G. FINLAYSON,
SAFETY ANCHOR FOR WINDOW CLEANERS,
APPLICATION FILED JAN. 25, 1918.

1,274,404.

Patented Aug. 6, 1918.

UNITED STATES PATENT OFFICE.

MURDO G. FINLAYSON, OF CHICAGO, ILLINOIS.

SAFETY-ANCHOR FOR WINDOW-CLEANERS.

1,274,404.

Specification of Letters Patent.

Patented Aug. 6, 1918.

Application filed January 25, 1918. Serial No. 213,645.

To all whom it may concern:

Be it known that I, MURDO G. FINLAYSON, a citizen of the United States, residing at Chicago, in the county of Cook and State 5 of Illinois, have invented certain new and useful Improvements in Safety-Anchors for Window-Cleaners, of which the following is a specification.

This invention relates to safety anchors 10 for window cleaners of the general type employed on tall buildings as a permanent means of attachment and anchorage for the safety ropes or straps with which each window cleaner who works upon the outside of 15 the building is equipped.

It was formerly the practice to screw a 20 pair of lag screws into each side of the window casing in predetermined space relation, and the headed outer ends of these screws which were left projecting beyond the outer 25 face of the casing served as the anchors to which the ends of the safety rope or strap were attached. Many serious accidents have resulted from failure of these lag screws to hold, either by reason of rusting of the 30 threads or rotting of the wood so that the screws would pull out. As the result of these accidents the use of lag screws as anchors for this purpose have been practically abolished.

One of the primary objects of my present invention is the provision of an anchor which can be so securely fastened and anchored to the building structure that all possibility of its giving way is eliminated, with 35 the result that the anchor can be used indefinitely without danger of accidents.

Another object of my invention is to provide an anchor which can be used either in 40 connection with a wooden window frame, or can be anchored in the stone or brick work adjacent the window when metal window casings are employed as they frequently are in modern building construction.

To facilitate the understanding of my invention, I have illustrated on the accompanying drawings preferred embodiments thereof from inspection of which, when considered in connection with the following 45 description, my invention and many of its inherent advantages should be readily under-

stood and appreciated by those skilled in the art.

Referring to the drawings:

Figure 1 is a transverse view through a 55 window frame showing my invention applied thereto;

Fig. 2 is a similar view showing a different form of building structure equipped with 60 my invention;

Fig. 3 is a transverse sectional view showing another form of my invention anchored in a brick wall adjacent to a window casing;

Fig. 4 is a face view of the structure 65 shown in Fig. 3;

Fig. 5 is a transverse sectional view through one of the anchor rods; and

Fig. 6 is a similar view showing a differently shaped rod.

From an inspection of the drawings, and 70 particularly Fig. 1 thereof, it will be observed that reference character 7 indicates generally the window casing, comprising the outer member 8, the inner member 9, and the transverse member 11. The upper and 75 lower window sash shown diagrammatically and indicated by reference numerals 12 and 13, respectively, are guided in the window casing in the usual manner, the upper sash being guided between the outer member 8 80 and the central guide strip 14, and the lower sash being guided between the parting strip 14 and an inner guide strip 15. The structure thus far described is of well-known construction and does not constitute part of 85 my present invention.

The anchor forming the subject-matter 90 of my present invention is adapted to be securely fastened to the window casing so as to leave projecting lugs at the outer side to which the safety ropes or straps of the window cleaner may be attached. The anchor comprises a member 16 adapted to abut against the outer face of the window casing and serves as a wall engaging abutment and 95 also a spacer bar as will appear hereinafter. This member is provided near each end with an opening adapted to receive one of the anchor rods 17 preferably made of wrought or rolled metal. These rods are 100 provided at their outer ends with heads 18, and adjacent these heads with tapered

shanks 19, the apertures through the members 16 being correspondingly tapered and adapted to snugly fit the shanks 19. The apertures furthermore are of such size that 5 they will slip onto the tapered shanks of the rods only a limited distance with the result that the headed ends of the rods project outwardly beyond the member a predetermined distance so as to afford ready attachment for the clips with which the safety 10 ropes of the window cleaners are equipped. The purpose of the member 16 is to space the projecting ends of the rods the requisite distance apart, to insure projection of the 15 headed ends of the rods the requisite distance outwardly from the window casing so that the safety clips can be readily attached thereto, and also to prevent the rods from turning or rotating so as to loosen them 20 from the anchor members at their inner ends which will be later described. In order to prevent this rotating movement of the rods with respect to the member 16, the rods and members are securely fastened together before the anchors are shipped. I have illustrated in Figs. 5 and 6 two ways of accomplishing this result. In Fig. 6 the shank 19 and the tapered opening 21 through the member 16 are both circular in form, and 30 rotative movement of the rods with respect to the member is prevented by spot-welding the member to the rods. The spot-welding operation fuses the metal of the rods with the metal of the member 16 so that they 35 come integrally united and rigidly secured together. In Fig. 5 the result is secured by making the tapered shank 19 square instead of round, the tapered opening 22 in the member 16 being correspondingly shaped so 40 that when the rods are firmly wedged into the openings rotative movement of the rods with respect to the member is precluded, and the spot-welding operation in this form is not entirely essential, although the welding 45 may be employed if preferred to make a more rigid connection.

The devices are shipped with the two rods inserted through the member 16 and attached thereto as previously described, and 50 when they are to be applied parallel holes are bored through the window casing from front to rear to accommodate these rods 17, as shown in Fig. 1. The inner ends of the rods will project inwardly beyond the inner 55 member 9 of the casing, and they are securely anchored against longitudinal withdrawal by screwing a nut 23 upon the inner end of each rod. In order to insure against the nut 23 becoming accidentally loosened, 60 a split spring washer 24 is preferably interposed between the nut 23 and the inner face of the member 9. Since the rods are held 65 against rotative movement by the member 16, it will be manifest that the probability 65 of the rods becoming loose or unfastened is

reduced to a minimum, particularly in view of the fact that the nuts 23 are threaded onto the rods tightly so as to draw the member 16 snugly against the outer face of the casing.

In Fig. 2 the window casing is of the same general construction as that shown in Fig. 1 and the anchor is substantially the same in all respects. In this instance, however, the building structure includes a molding 25 disposed upon the outer face of the window casing, and the member 16 abuts against this molding instead of directly against the window casing. The rods 17 in this instance are necessarily a little longer, 75 but it should be understood that the length of these rods is always proportioned to meet the requirements of the building to which they are to be applied.

In Figs. 3 and 4 I have illustrated a form 80 of my invention which is particularly applicable to brick buildings which usually employ metal window casings. The anchor in this instance is set directly in the brick wall adjacent to the casing. The member 16 and 85 the outer ends of the rods 17 are constructed and assembled similarly to those previously described, but their inner ends are permanently secured together by bar 26 which is either welded to the ends of the rods, or the 90 ends of the rods are threaded and the bar is provided with correspondingly tapped openings into which the ends of the rods are threaded before the member 16 is engaged with the shanks of the rods to prevent 95 their rotation. In some instances it may be desirable to further strengthen the threaded connection by spot-welding the rods and bar together. The rods, the bar 26 and the member 16 in this form of the invention are 100 all assembled and rigidly secured together before the anchor is shipped, and when it is to be installed it is placed in position during the construction of the side wall, and the bricks 27 of the wall are built around 105 and between the rods, as shown in Figs. 3 and 4, thus firmly and permanently anchoring the device in the wall with the headed ends of the rods projecting adjacent to the metal window casing 28 in position to be 110 engaged by the safety clips of the window washer's equipment.

It is believed that my invention will be readily understood from the foregoing without further description, and while I have 115 shown and described two practical and preferred embodiments of the invention, it should be appreciated that various changes in the size, shape, proportion and manner of assembly of the various parts may be 120 resorted to without departing from the spirit of the invention as defined in the following claims.

I claim:

1. A safety anchor comprising a pair of 130

- substantially parallel wrought metal rods, a combination wall-engaging-abutment and spacer-bar through which the rods pass and with which they are engaged to prevent rotation of the rods in the bar, said rods being shaped a predetermined distance inwardly from the front ends of the rods for rigid engagement by the spacer bar in its relative position, the front end of each rod having a head, and means applicable to the rear ends of the rods for engagement with a wall to prevent longitudinal withdrawal of the rods.
2. A safety anchor comprising a pair of substantially parallel wrought metal rods, a combination wall-engaging-abutment and spacer-bar through which the rods pass, said rods being shaped a predetermined distance inwardly from the front ends of the rods for rigid engagement by the spacer bar in its relative position, the front end of each rod having a head, and means applicable to the rear ends of the rods for engagement with a wall to prevent longitudinal withdrawal of the rods.
3. A safety anchor comprising a pair of substantially parallel cylindrical wrought metal rods, each rod having a head at its front end and tapered from the head rearwardly a predetermined distance, a combination wall engaging abutment and spacer bar through which the rods pass, said bar normally engaging the tapered portion of the rods and wedged thereon to prevent rotation of the rods, and means applicable to the rear ends of the rods and for engagement with a wall to prevent longitudinal withdrawal of the rods.

MURDO G. FINLAYSON.
